Primary Examiner — Jae Liang*Assistant Examiner* — Jane Yoon(57) **CLAIM**

The ornamental design for a travel bag as shown and described.

DESCRIPTION

FIG. 1 is a front, right and top perspective view of a travel bag showing my new design;

FIG. 2 is a rear, left and bottom perspective view thereof;

FIG. 3 is a rear, left and top perspective view thereof, shown in an open configuration;

FIG. 4 is a front, right and bottom perspective view thereof, shown in an open configuration;

FIG. 5 is a front, right and top perspective view thereof, shown with the cover detached from the travel bag;

FIG. 6 is a front elevational view thereof;

FIG. 7 is a rear elevational view thereof;

FIG. 8 is a left view thereof;

FIG. 9 is a right view thereof;

FIG. 10 is a top plan view thereof;

FIG. 11 is a bottom plan view thereof;

FIG. 12 is an enlarged view of the portion labeled as 12 in FIG. 1; and,

FIG. 13 is an enlarged view of the portion labeled as 13 in FIG. 3.
